UNITED STATES PATENT OFFICE.

BRUCE EDWARD BLISS, OF WICHITA, KANSAS.

TWO-PART INTERLOCKING TIRE.

1,311,309.

Specification of Letters Patent. Patented July 29, 1919.

Application filed February 15, 1919. Serial No. 277,240.

To all whom it may concern:

Be it known that I, BRUCE EDWARD BLISS, a citizen of the United States, and a resident of Wichita, in the county of Sedgwick and 5 State of Kansas, have invented certain new and useful Improvements in Two-Part Interlocking Tires, of which the following is a description, referring to the accompanying drawings, which form a part of this specification.

The object of the invention is to provide a casing composed of two parts the object of which is that when the tread is worn through the outside casing it can be replaced without 15 professional assistance, also that the life of the case may be increased at a lesser cost and also to increase the life of the fabricated portions of the casing by increasing and distributing the elastic members and also the 20 possibility of sliding the outer casing whereby a hole protruding through both members may not communicate directly to the inner tube and also to provide means to prevent a sliding motion in any direction of the outside 25 side casing, and further mechanical means to insure perfect contact and stability of position between the two casings, thereby providing a practical casing for automobile and kindred uses.

30 In the drawings Figure 1 is a top view of the tire with a portion of the outside casing removed to show the channels which continue on the periphery of the inner casing.

Fig. 2 is an inside view of Fig. 5 showing the protruding ribs which coincide with the channels shown in Fig. 1.

Fig. 3 is a cross section on line A—A Fig. 1 looking in the direction of arrow.

Fig. 4 is a sectional view on line B—B 40 Fig. 1 looking in the direction of arrow.

Fig. 5 is a sectional view on line C—C in Fig. 2 looking in the direction of arrow.

Similar characters of reference indicate 45 corresponding parts throughout the drawings.

Referring to the drawings D is an outside casing adapted to fit closely over the surface of an inside casing substantially as shown in sectional view Fig. 3; said casing is composed of a plurality of layers of fabric as 50 shown at E and elastic body as shown at F said fabric being well cemented together and also cemented to the elastic body. G is an inside casing composed of a plurality of 55 layers of fabric and elastic body all firmly

cemented together and formed substantially as shown in the drawings. H are the layers of fabric and I is the elastic body. J is a channel extending longitudinally around in the periphery of the inside casing G. K is a plurality of transverse channels intersecting at intervals with channel J as shown in Fig. 1. L is a protruding rib with beveled corners adapted to seat in channel J. M are the transverse ribs adapted to seat in channels K. The said ribs L and M are placed to coincide and enter into the channels J and K, the object of which is to prevent casing D from slipping around on casing G or creeping longitudinally during the rotation of the wheel on the road, and as a further means to bind casing D in perfect contact to casing G metallic wires N¹ and N² are firmly bound in the edges of casing D and a groove is cut in casing G as shown at O¹ and O² and the casing placed on a wheel rim as shown at P and the inner tube inflated will crowd inner edges of the casing against the flanges of the rim as shown at Q¹ and Q² rendering it impossible for the outside casing to be removed therefore perfect contact is made between the inside and outside casing.

Various sizes and shapes of tires may be constructed and to conform to the shape of 85 different makes of standard rims to hold the casings in perfect contact substantially as shown and described.

Having thus described my invention, what I claim as new and desire to secure by Letters Patent, is—

1. In an outer casing for pneumatic tires composed of a plurality of layers of fabric and elastic body elements integrally cemented together; a centrally situated longitudinally extending rib protruding from the inner wall face of said casing and intersected at spaced intervals by transverse ribs similarly protruding from said wall face; the edges of said casing being inwardly bent 95 and fabricated to form inextensible flanged members for the purposes as specified.

2. In a casing for pneumatic tires composed of a plurality of layers of fabric and elastic body elements integrally cemented together; a centrally situated longitudinally extending channel formed in the periphery thereof and intersected at spaced intervals by channels transversely arranged in said casing periphery; the edges of said casing 105 110

forming beads, each bead having a grooved inwardly formed recess for the purposes as specified.

3. In combination as a shoe for pneumatic tires, an inner casing enveloped by an outer casing; each of said casings comprising a plurality of layers of fabric and elastic body elements integrally cemented together; a centrally situated longitudinally extending channel formed in the periphery of said inner casing and intersected at spaced intervals by channels transversely arranged in said casing periphery; and edge beads of said inner casing having grooves inwardly formed therein as specified; a centrally situated longitudinally extending channel formed in the periphery of said inner casing and intersected at spaced intervals by channels transversely arranged in said casing periphery; and edge beads of said inner casing having grooves inwardly formed therein as specified; a centrally situated longitudinally extending rib protruding from the inner wall of said outer casing and intersected at spaced intervals by ribs transversely protruding from said inner wall of said casing; said protruding longitudinal and transverse ribs of the outer casing engaging within said longitudinal and transverse channels of the inner casing as specified; and edges of said outer casing inwardly bent and fabricated to form inextensible flanged members and engaged within the adjacent grooves in the edge beads of said inner casing whereby inflation of an inner tube included within said inner casing will act to maintain engagement of the flanged members of the outer casing within the grooved beads of said inner casing and against the flanged rim elements of the wheel as specified.
4. In combination as a shoe for pneumatic tires and mounted on a rim of a wheel and between the flanges thereof, an inner casing enveloped by an outer casing; each of said

casings comprising a plurality of layers of fabric and elastic body elements integrally cemented together; a centrally situated longitudinally extending channel formed in the periphery of said inner casing and intersected at spaced intervals by channels transversely arranged in said casing periphery; and edge beads of said inner casing having grooves formed therein as specified; a centrally situated longitudinally extending rib protruding from the inner wall of said outer casing and intersected at spaced intervals by ribs transversely protruding from said inner wall of said casing; said protruding longitudinal and transverse ribs of the outer casing engaging within said longitudinal and transverse channels of the inner casing as specified; and edges of said outer casing inwardly bent and fabricated to form inextensible flanged members and engaged within the adjacent grooves in the edge beads of said inner casing whereby inflation of an inner tube included within said inner casing will act to maintain engagement of the flanged members of the outer casing within the grooved beads of said inner casing and against the flanged rim elements of the wheel as specified.

BRUCE EDWARD BLISS.
